FULLING MILL

Frank E. Morrill, North Adams, Mass., assignor to
The James Hunter Machine Company, North
Adams, Mass., a corporation of Massachusetts

Application August 13, 1943, Serial No. 498,604

12 Claims. (Cl. 26—21)

This invention relates in general to fulling mills used in the finishing of wool fabrics, and more specifically to the crimp boxes employed in conjunction with the squeeze rolls of such mills to felt, condense, and compact the fabric. In particular, it relates to the means used for variably weighting the hinged tongue of the crimp box to adjust the pressure of this tongue to the needs of the particular fabric being fulled and to the rate of felting action required.

In operating a fulling mill, the degree of lengthwise fulling, that is, the shortening and compacting of the fabric in the direction of extent of its warps, is governed by the degree of the pressure of the hinged tongue of the crimp box downward upon the folds of fabric forced by the squeeze rolls into the passage between the sides and bottom of the crimp box and the hinged top thereof, this top being weighted to apply a constant but yielding degree of resistance to the travel of the cloth crammed into the crimp box in pleated form by the pushing action of the squeeze rolls which feed the cloth continuously through the mill. The earliest method of weighting the tongue was to apply weights of various mass and numbers to the free end of the tongue, pinning or otherwise attaching them in fixed position. Subsequently, the conventional prior practice has been to employ a link and lever system in which weights of the desired mass are hung on the lower ends of rods hanging down at one or both sides of the fulling mill, outside of the housing, and near the rear of the mill, the rods exerting a constant downward pull on arms on a rockshaft extending across the top of the mill and the rockshaft being equipped with other arms connected by links to the free ends of the tongue to press downward correspondingly on the tongues, auxiliary springs being adjustably anchored on the weight-holding rods by collars and bearing against the guides of these rods to oppose the downward pull of the weights so as to permit minor variations in the pressure exerted by the weights, and also to damp out vibrations of the weights causing uneven action.

This conventional weighting system has left considerable room for improvement, since it requires a separate rockshaft, link, lever and weight system for each of the two to four crimp boxes in a single mill, or else when employing a common rockshaft causes the tongue engaging that line of cloth whose pleats are momentarily the thickest to exert the major degree of pressure, thus lifting and correspondingly relaxing the pressure of the other tongues, resulting in un-

even fulling. In addition to the nuisance and incomplete flexibility of the system of changing the weights which must be employed, the operator has to leave his station at the front of the mill whence he observes and controls the fulling action and walk to the rear of the mill to modify the weighting, which requires him to pass between and in close proximity to the belts or other driving means of the aligned series or battery of fulling mills as usually installed, thus involving personal hazard of being caught and injured by the drives which usually are inadequately guarded; or where a series of mills is set up in line in compact relation, the operator is required to detour around the end of the line to get at the weights, thus involving loss of time. The same trip to the rear of the mill has to be made, and in addition a strenuous physical effort is required, when the weights have to be lifted by hand in order to raise the tongues in threading up the mill or running out the cloth. It is the practice to hold the weights and tongues thus lifted by shifting the collars which anchor the auxiliary springs on the weight rods down along the weight rods and then tightening up the collars to sustain the parts in this relation, which has resulted in repeated accidents in which the operators have been injured by the falling of the weight rods and quick descent of the levers attached thereto when the collars are loosened to put the tongues in action, through failure to realize the amount of weight hung on the rods.

With the object of overcoming these drawbacks, and in general making simpler, safer and more convenient the adjustment of the weighting of the tongues as well as the acts of lifting and lowering the tongues, the invention consists essentially in providing a weight permanently installed directly on the tongue of each crimp box, adjustable along the tongue toward and from the hinge of the latter so as to give a continuous range of variation from maximum to minimum of its effective leverage, bias, or torque in depressing the tongue, each weight preferably being individually shiftable along the tongue from the operator's station at the front of the fulling mill. Desirably, also, the movement of the weight into its position of minimum leverage also lifts the tongue to provide for threading up the mill or running out the cloth, and in addition the mechanism for shifting the weight also gives an accurate indication, by scale and pointer, of the relative degree of pressure being exerted by the tongue so that such pressure is always

known and can be reestablished after change when the same setting is again desired.

Other aims of the invention, and the manner of their attainment, are as set forth hereinafter.

An illustrative embodiment of the invention is shown in the accompanying drawings in which—

Fig. 1 is a side view in vertical section through a conventional fulling mill equipped with the invention, taken on line 1—1 of Fig. 2, and showing the action of the weighted tongue on the cloth packed into the crimp box.

Fig. 2 is a horizontal section on line 2—2 of the fulling mill of Fig. 1.

Fig. 3 shows a portion of the parts of Fig. 1, illustrating the relationship when the invention 15 device is used to raise the tongue.

Fig. 4 is a view similar to Fig. 3, showing the relation of the parts when adjusted to exert nearly maximum pressure by the tongue.

Fig. 5 is a detail view showing the manually 20 operable control means for the shiftable weight, together with the indicator which shows the relative degree of weighting being attained.

Fig. 6 is a section on line 6—6 of Fig. 5.

The fulling mill may be of any conventional or preferred design, that illustrated herewith being of common form and comprising a housing 1 of wood with the usual outside metal framing 2, in which are rotatably mounted the opposed pairs of fulling rolls 3 fixed on driven shafts 5 supported in suitable bearings in the outside framework. The usual separator grid 7 guiding the several lines of cloth 9 in parallel paths and pivotally mounted on the rockshaft 11 of the stop motion so as to stop the transmission of power to rolls 3 when tangling occurs, is shown, as is also the guide roll 13 above the grid, around which the cloth changes its direction to enter the rolls.

The crimp boxes 15 are of the usual form, 40 each comprising side walls 17 and a bottom 19 fitting closely up to a cooperating pair of the rolls 3, and mounted as upon a cross-girt 21 extending across the mill from one side wall 2 thereof to the other. U-shaped braces 23 fixed to the sides 17 surround the two sides and the bottom of the box, and are united by a tie rod 25, above the sides, which forms the pintle for the hinge 27 of the tongue 29 forming the cover of the box. Here, as usual, the top, bottom, sides, and tongue of the box are shown as made of wood, though they are occasionally made of metal. The tongue 29 swings up and down freely between the side walls 17.

The improved weighting means is in the form illustrated herein made to roll lengthwise of the tongue, to facilitate the shifting of its position along the tongue to vary the torque exerted upon the tongue without need to change the mass of the weight. Thus, it comprises the cast-iron roll 30, weighing from 50 to 130 pounds, depending on the class of goods fulled and the type of the mill, rotating on an axle 31 fixed in the lower ends of arms 33 of a hanger or fork of inverted U-shape, to the midportion or transverse part of which is attached by bolts 35 a nut 37 threaded onto a screw 39 extending obliquely upward and forward from the interior of the fulling mill and out through slots formed in the low wall at the front of cover 40, and connected by a universal joint 43 to the rear end of a shaft 45 rotating in bearing 47 on a sleeve 49 fixed on a transverse supporting rod 51 fixed in brackets 53 on the outside frame of the mill, and in bearing 55 on a bracket 57 fixed on a cross-girt 59

of the mill. Shaft 45 is equipped with a hand-wheel 61 on its free end, by which it is manually rotated, and near its other end with a collar 61 preventing endwise movement in its bearings. A portion of the length of shaft 45 is screw threaded, and on this threaded portion rests a half-nut 63, Figs. 1 and 6, of saddle shape having laterally extending wings which stand out sidewise beyond the depending edges of the flanges of an inverted channel iron member 65 which is attached by screws 67 to the tops of bearings 49, 55. A pointer 69 is applied to the end of one of the wings, cooperating with a scale 71 applied to the side of the channel member 65. Thus, by turning hand-wheel 61 the shaft 45 and the screw 39 are rotated in either direction to shift the rolling weight 30 toward or from the fulcrum of tongue 29, thereby varying the torque exerted on the tongue and the latter's pressure on the cloth from the maximum amount obtained when the rotation of screw 39 rolls the weight out to the free end of the tongue, to a condition where no weight at all, either of the roll or of the tongue 29, is applied to the cloth passing through the crimp box. As the indicator 69 travels along its scale 71 in exact accord with the advance or retraction of roll 30, the relative position of the roll, and hence the relative degree of weighting of the tongue 29, is made known at all times to the operator while standing in his working position at the front of the mill, and also is made capable of being instantly varied by him without leaving his position and of being infinitely adjusted from zero to maximum by the simplest kind of manual operation with negligible effort. A stop 73 on the end of screw 39 prevents the roll-positioning nut 37 from escaping from its screw.

To lift the tongue, for purposes of threading up the mill or running out the cloth, the roll 30 is arranged to roll on tracks comprising angle irons 75 fixed in spaced and parallel relation on longitudinal wooden cleats 77 applied to the top surface of tongue 29, the roll rolling on the transversely extending webs and being guided between the vertical webs of these angle irons; and the ends of the angle irons are turned up at right angles over the pintle 25 as indicated at 79 and furnished with extensions 81 joined by a cross-bar 83 which is engaged by the edge of fork 33 when roll 30 is retracted fully toward the front of the mill. Continued manipulation of hand-wheel 61 following such engagement causes the fork to pull forwardly on cross-bar 83, thus swinging tongue 29 upwardly on pintle 25 substantially to the top of side walls 17, as shown in Fig. 3, leaving the passage through the crimp box unobstructed by the tongue. The opposite ends of the angle iron guide rails 75 are also turned up and braced by a cross-bar 85, which also serves as a stop for the roll 30 in its movement toward the free end of the tongue.

In this manner the lifting of the tongue is also accomplished by the operator with a minimum of effort by the same operation of the controls without leaving his position at the front of the machine. Since the weighting roll 30 assumes a position first directly above the pintle 25 of the tongue and then slightly beyond such pintle, as the tongue is being raised, the tongue is in effect completely unweighted and in fact counterbalanced or overbalanced by the weight during the lifting of the tongue.

As is plain from the foregoing, it is within the contemplation of the invention to employ instead

of the rolling weight a weight sliding or otherwise shiftable along the tongue, by remote control means such as a chain and sprockets or a cable and windlass performing the equivalent function of the screw 39.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but

What I do claim is:

1. Weighting means for the tongue of a crimp box, in a fulling mill or the like, comprising the combination with a pivotally mounted tongue of a weight acting to depress the tongue, and remote-control means operable from a position in front of the fulling mill shifting the weight toward and from the pivot of the tongue.

2. Weighting means for the tongue of a crimp box, in a fulling mill or the like, comprising the combination with a pivotally mounted tongue of a weight resting on the tongue and acting to depress the tongue, and remote-control means shifting the weight toward and from the pivot of the tongue.

3. Weighting means for the tongue of a crimp box, in a fulling mill or the like, comprising the combination with a pivotally mounted tongue of a weight shiftable along the top of the tongue toward and from the pivot thereof, and manually-actuated means operable from a position in front of the fulling mill shifting the weight toward and from the pivot to vary the torque exerted by the weight on the tongue.

4. The combination as set forth in claim 3, in which means is provided, readable from the said position, indicating the relative position of the weight with respect to the pivot of the tongue.

5. In a fulling mill, in combination, a crimp box, a tongue pivotally mounted in connection therewith, a weight resting on the tongue and tending to depress the tongue into the box, and screw means shifting the weight toward and from the pivot of the tongue.

6. In a fulling mill, in combination, a crimp box, a tongue pivotally mounted in connection therewith, a weight resting on the tongue and

tending to depress the tongue into the box, and screw means operable from a position in front of the fulling mill shifting the weight toward and from the pivot of the tongue.

5 7. In a fulling mill, in combination, a crimp box, a tongue pivotally mounted in connection therewith, a roll resting on the tongue and tending to depress it into the box, screw means in connection with the roll shifting it along the tongue toward and from the latter's pivot, and means located at the front of the mill for actuating such screw means.

10 8. In a fulling mill, in combination, a crimp box, a tongue pivotally mounted in connection therewith, a roll resting on the tongue and tending to depress it into the box, a nut in connection with such roll, a screw in engagement with the nut, a shaft flexibly connected to the screw to rotate the latter, and manually operable means at the front of the mill rotating the shaft to shift the roll along the tongue.

15 9. Weighting means for the tongue of a crimp box, in a fulling mill or the like, comprising the combination with a pivotally mounted tongue of a weight acting to depress the tongue when on one side of the pivot of the tongue, and shiftable to the other side of the said pivot to exert a force tending to lift the tongue out of the box.

20 10. In a fulling mill, in combination, a crimp box, a tongue pivotally mounted in connection therewith, a weight resting on the tongue and tending to depress the tongue into the box, remote-control means shifting the weight along the tongue, and means on the tongue engaged by the weight when thus shifted and acting to lift the tongue.

25 11. In a fulling mill, in combination, a crimp box, a tongue pivotally mounted in connection therewith, a member rigidly attached to and projecting from the tongue, and manually operable means movable lengthwise of the tongue to strike the projecting member and thereby lift the tongue away from the bottom of the box.

30 12. In a fulling mill, in combination, a crimp box, a tongue pivotally mounted in connection therewith, a manually operable member movable lengthwise of the tongue, and means projecting from the tongue engaged by said member in the course of its movement and thus lifting the tongue away from the bottom of the box.

FRANK B. MORRILL.
